US0D1056855S

(12) **United States Design Patent** (10) **Patent No.:** **US D1,056,855 S**
(45) **Date of Patent:** **** Jan. 7, 2025**

(54) **ELECTRICAL CONTACT ARRANGEMENT**(71) Applicant: **SAMTEC, INC.**, New Albany, IN (US)(72) Inventors: **Chadrick Paul Faith**, New Albany, IN (US); **Gary Ellsworth Biddle**, New Albany, IN (US); **Randall Eugene Musser**, New Albany, IN (US); **Jonathan Earl Buck**, New Albany, IN (US)(73) Assignee: **SAMTEC, INC.**, New Albany, IN (US)(**) Term: **15 Years**(21) Appl. No.: **29/937,846**(22) Filed: **Apr. 17, 2024****Related U.S. Application Data**

(60) Continuation of application No. 29/865,977, filed on Aug. 23, 2022, now Pat. No. Des. 1,028,904, which is a division of application No. 29/689,687, filed on May 1, 2019, now Pat. No. Des. 967,770, which is a continuation of application No. 29/579,623, filed on Sep. 30, 2016, now Pat. No. Des. 851,044.

Primary Examiner — Daniel J Domino*Assistant Examiner* — Lee D. Starr*(74) Attorney, Agent, or Firm* — BakerHostetler(57) **CLAIM**

The ornamental design for an electrical contact arrangement as shown and described.

DESCRIPTION

FIG. 1 is a bottom, left, front perspective view of an electrical contact arrangement showing our design;

FIG. 2 is a top, right, rear perspective view thereof;

FIG. 3 is a bottom plan view thereof;

FIG. 4 is a top plan view thereof;

FIG. 5 is a front elevation view thereof;

FIG. 6 is a rear elevation view thereof;

FIG. 7 is right plan view thereof; and,

FIG. 8 is a left plan view thereof.
